Inventor:
J. Franz.

UNITED STATES PATENT OFFICE.

JOSEF FRANZ, OF BISCHOFSWERDA, GERMANY.

COP TUBE.

Application filed December 15, 1926, Serial No. 154,952, and in Germany June 9, 1925.

In order to prevent the yarn in the shuttle of a weaving loom from getting loose on the cop tube under the influence of the shocks to which the shuttle is subjected, 5 cop tubes are sometimes provided with annular or spiral ribs. As ordinarily made, these ribs are liable to tear fine yarn and give rise to waste of material. The object of the present invention is to provide such 10 tubes with ribs which are able to prevent a loosening of the yarn without tearing the same, and the invention consists in forming the ribs by the introduction of a thread or threads between the paper layers when the 15 tube is made. The layers are pasted together, and as the thread is covered by the paper, a very smooth rib will be produced whereby the yarn cannot be torn.

Fig. 1 of the accompanying drawings 20 represents a view of the cop tube according to one construction,

Fig. 2, a view showing the method of 25 making the same,

Fig. 3, a view of another form of the 30 tube, and

Fig. 4, a view showing the method of 35 making the latter tube.

The cop tube *c* is made in known manner by the winding of the gummed or pasted

30 paper strip *a* on to a conical core. The tube is provided with ribs *d* or *d'* which according to the invention are formed by the introduction of a thread or threads between the paper layers. Annular ribs *d* are formed, as shown in Fig. 2, by feeding 35 a plurality of threads *b* in between the paper layers. In the case of a spiral rib *d'*, a thread *e* is used which is guided along the tube as the latter is made, as indicated in Fig. 4.

40 As the thread or threads are embedded in the paste and covered by the paper, a smooth rib will be produced, and the production of the ribs does not materially complicate the making of the tube.

45 I claim:

1. A cop tube composed of paper layers which are pasted together, and threads embedded between said paper layers so as to 50 form circumferential ribs.

2. A method of making ribbed cop tubes out of paper and thread, consisting in winding a paper strip together with the thread about a core so that the thread becomes embedded between the paper layers and produces the ribs, the layers being pasted together over the thread.

55 JOSEF FRANZ.
